CLAIM

The ornamental design for a shoe, as shown and described.

DESCRIPTION

FIG. 1 is a bottom view of a shoe showing our new design; FIG. 2 is a bottom rear perspective view thereof; and, FIG. 3 is a bottom front perspective view thereof. The unshaded area forms no part of the claimed design. The broken lines depicting the remainder of the shoe form no part of the claimed design.

1 Claim, 3 Drawing Sheets(56)
